(57) **CLAIM**

The ornamental design for an ink filter housing, as shown and described.

DESCRIPTION

FIG. 1 is an isometric view of an ink filter housing showing our new design;

FIG. 2 is a top plan view thereof;

FIG. 3 is a bottom plan view thereof;

FIG. 4 is a right-side elevation view thereof;

FIG. 5 is left-side elevation view thereof;

FIG. 6 is a front elevation view thereof; and,

FIG. 7 is a rear elevation view thereof.

The broken lines shown in the figures are for the purpose of illustrating portions of the ink filter housing and form no part of the claimed design.
